radiation may be used with convection currents but is preferably used with air delivered under pressure as by a fan and guided by a casing such as indicated at 11a in the accompanying drawings.

5 When the sections are connected together in series they are so connected by a hexagon nipple designated 12. When so connected the space between the marginal edges adjacent the fins of the adjacent sections in the example I have cited is $1\frac{1}{4}$ inches. The design, however, is not limited to this dimension since by use of longer or shorter nipples this dimension can be varied.

10 In actual test of this radiator of my invention in comparison with the best radiator sections and the most efficient known in the art of cast iron radiators today, I secure the following results:

15 When comparing the two radiators at equal friction, the radiator of my invention weighs 20% of the old radiator, requires 63% of the space of the old radiator, and provides 119% of the heating surface of the old radiator. I further find that two sections or stacks of the present radiator would do the work of 2.4 stacks of the old radiator.

20 When comparing the best radiator of the old art with my present invention on the basis of equal velocity of the air passing thereover, I find that my new radiator of this invention weighs 71% of the old radiator, takes up 68% of the space occupied by the old radiator and has 128% of the heating surface of the old radiator. Two stacks of the new radiator do the work of 2.3 stacks of the old radiator. The radiator of this invention requires 83% of the friction of the old radiator. Furthermore, the new radiator stands a maximum hydraulic pressure of 200 pounds gauge as compared with the maximum pressure of the old radiator of 150 pounds.

25 The new radiator is, therefore, 30% lighter than the old radiator and occupies 35% less space. It is superior whether compared on the basis of equal friction or equal velocity. The significance of these comparisons will be apparent when it is understood that one of the primary uses of this radiation is in forced blast systems where the space occupied, the weight involved, the resistance to air flow and the rate of heat transfer are such vital factors as to constitute the difference between failure and success in the

30 operation of a forced draft system. The radiator of my invention makes it possible to use cast iron with all of its advantages in competition with radiators of other materials. While I do not desire to confine my invention to cast iron, yet its advantages become apparent when cast iron is used as a medium of its embodiment and the basis of its comparison even with other materials in other designs.

35 While not intending to limit my invention to all or a large part of the following features, nevertheless the following is a summary of the numerous features of operation and construction inherent in the construction and method of operation of the apparatus of my invention:

(1) An oblong, in section, steam body whose flat sides carry undulatory fins; while the sides of the steam-containing body are flat as shown in the drawings, yet they could be made undulatory so long as they preserved the herein-after mentioned principle of "undetached undulatory flow."

(2) The width of the fins is constant and the edge of each fin is parallel to the flat face of the radiator body.

(3) The fins are undulatory out of a horizontal plane but are not undulatory out of a vertical plane and, therefore, there is no marked lateral change in direction of the air stream by reason of either the fins or of the body of the radiator.

5 (4) The fins completely encircle the entire radiator body both on the sides and on the ends thereby assisting in the entering of the air and the exit of the air and at the same time improving the radiating qualities of the structure.

(5) Such an arrangement provides a relief of the inlet between sections to reduce the vena contracta loss where the air enters. There is a similar reduction of the loss at the exit in the same manner for the same reason.

(6) The total width of the fins is so proportioned as to constitute substantially the total width of the body.

(7) The undulations of the fins are sufficient to bring about a wiping action of the air on the flat surface of the body to reduce the air film on the surface of the body to increase heat transfer but such undulatory arrangement is not sufficient to set up turbulence or resistance to air flow so that the air movement will be sufficiently rapid to carry away the heat for maximum efficiency. The foregoing statement must be read in the light of the understanding of the principle of undetached undulatory flow hereinafter explained. The fluid stream undulates to a point approaching but never attaining detached flow.

(8) The undulations of the rib or fin in this section in this instance have a depth only of one-thirteenth of the distance between the crowns of the undulations. The undulations must be of such a character as to preserve the principle of this invention of undetached undulatory flow, which is a new feature of the invention and from which results the efficiency secured.

(9) The end ribs are heavy, wedge-shaped terminal ribs for reinforcing purposes.

(10) The wall thickness is substantially twice as thick as the rib thickness while the rib or fin surfaces are twice as great as the body surface between the ribs so that the thinner ribs for heat transmission present twice as great a heat radiating surface.

(11) The ribs are progressively thinner the further they are from the heat source so that there will be uniform distribution of heat throughout the rib.

(12) The ribs are spaced on adjacent bodies from one another by a distance approximately the same as the combined width of adjacent ribs in order to provide a sufficient body of moving air to permit a velocity while securing maximum heat transfer. It is not intended, however, to limit the probable application to this ratio.

(13) The straight side walls of the body give a free sweep for the transverse steam flow to reduce the internal film on the interior of the body of the radiator, thus increasing the efficiency of the heat transfer.

(14) The undulation of the fins without change of direction of the air body moving between them is sufficient to disturb the air film on the outside of the body without back pressure and without detachment so that the undetached undulatory flow is secured.

(15) The air flow between the fins is of such a nature that it is continuous with an unde-

tached contact with all surfaces of the metal boundary. The surface must not be deprived of the close and intimate contact with the fluid in order to prevent the loss in efficiency in the transfer of convection heat. The formation and subsequent detachment of large eddies of air due to turbulence without intimate contact results in the expenditure of energy without adequate heat transfer. The present invention has the minimum area of boundary wall with the greatest transfer of heat with the least energy expenditure. This is due to the fact that the fluid stream is caused by the fins to undulate to a point approaching but never attaining detached flow. The eddies are correspondingly reduced in size and the speed thereof accelerated. This secures intimate contact at increased velocities with the continual change of the fluid particles from the center of the air stream to the boundary. Due to the alternate increased and decreased velocity in pressures, the air particles that are heated are continually supplanted by the cooler inner stream particles. So long as the angularity is sufficiently minor, the energy expenditure necessary to produce the undulations, which energy expenditure is proportional to the angular change in direction added to the increased frictional resistance due to the velocity increase will be sufficiently small as to be of no importance. The slightly increased demand for energy due to the undulations has no consequence in view of the greatly improved rate of heat transfer produced by the undetached undulatory flow secured by this construction.

And, furthermore, the foregoing indicates that my invention and its physical features take into account these important propositions:

(1) The elimination of back pressure and the increase of velocity by using a gentle undulatory flow of the air through channels of metal having substantially equal area on three sides and substantially equal heat distribution throughout the surface of the metal.

(2) The movement of the air through such channels as to break up any air film on the surface of the metal without setting up undue turbulence and back pressure.

(3) The use of straight walls (or undulatory walls without detachment) of a main body so that the maximum velocity of the gas, water or steam wipes the film away on the interior of the wall decreasing its thickness and increasing heat transfer; by having the straight body the film on the interior and the exterior of the wall is reduced by the velocity of the steam and the velocity of the air.

(4) The essence of this invention is the discovery of the principle referred to herein as that of "undetached undulatory flow." This means that the fluid stream undulates to a point approaching, but never attaining, detached flow. Heat transfer is in proportion to the reduction in size of the eddies in diameter and the acceleration of those eddies to secure a more intimate contact and an increased velocity with the cooler air near the center of the stream and a continuous substitution of the fluid particles from the center of the stream to the boundary.

As a basis for a full understanding of the principles of my method of heat transfer and a typical construction by which my method may be practiced, the following premises should be understood as the basis for the practice of my invention.

As my purpose is to effect a heat transfer from the fluid having a relatively high specific heat, such as a prime fluid comprising steam through containing boundaries, such as cast iron, to a fluid having a relatively low specific heat, such as the secondary fluid air, it will be understood that the prime fluid requires more contact area than the secondary fluid. Therefore, I project from the boundaries of the radiator body on the outside where the air is flowing gently undulatory surfaces of such undulation as to effect the practice of this invention. If the fins are made zigzag, in which various parts of the fins are at an abrupt angle to one another, then the object of the invention is completely destroyed. If the fins are made straight, again the object is destroyed.

The side walls may be either flat or undulatory, the latter preferred, but, in any event, with an uninterrupted surface which permits condensation to flow across the surfaces uniformly thus wetting and wiping the surface on the interior of the body with consequent increase in the rate of surface contact and the rate of heat transfer due to the condensation on the walls having a higher specific heat than the contained gaseous fluid in the case of steam.

The secondary fluid, such as air, on the outside of the body is confined by the prime surface and the two projecting adjacent undulatory fins are fixed to the prime surface and conduct heat therefrom. These fins are so designed as to provide a comparatively even flow of heat to the boundaries of the secondary fluid, and the spacing is such that the maximum heat, both of convection and radiation, is imparted with the minimum surface friction resistance to fluid flow. The parallel fins are given a slight undulatory effect in direction of the fluid flow and are carried completely around the ends of the radiator body.

The relation of the angularity at any point of these undulations must be such as to conform to the principles of turbulent flow that I observe and such undulations must be such that, at all points on them, there will be uninterrupted surface contact between the air and the cast iron surface.

The importance of this arrangement can best be understood by contrast with the prior art. In the case of parallel fins, without undulations, that is, straight, (Fig. 8) the fluid flow will have a velocity higher than the average at a point midway between the fins with a gradual decrease as the fin is approached. The friction of the fin surface on the fluid will cause minute swirls or eddies to form. These eddies revolving on independent axes will be detached and progressed down stream with the fluid flow but at much lower velocity than the true stream, thus retarding the heat transfer which is governed by a function of velocity at the point of contact of approximately the one-half power. These eddies further retard heat transfer in that they act as an insulating media between the surface and the fluid, and prevent the displacement of the film in contact with the surface by fluid in the main stream, the removal of this eddy film from surface contact and the replacement of eddying fluid with less highly heated fluid from the main stream; and the increase of velocity at or near the boundary is, therefore, of prime importance especially as the heat transfer is in the nature of a one-half power. It is apparent that the alternating increased and decreased velocities

RADIATOR

Otto G. Wendel, Buffalo, N. Y., assignor to The American Radiator & Standard Sanitary Mfg. Company, New York, N. Y., a corporation of Delaware

Application February 12, 1934, Serial No. 710,774

21 Claims. (Cl. 257—151)

My invention relates to a construction of radiator.

The purpose of my invention is to provide an apparatus to practice heat transfer from a fluid having a relatively high specific heat, known as a prime fluid, through containing boundaries, such as cast iron, to a fluid having a relatively low specific heat, denominated as a secondary fluid.

It is the object of my invention to provide a radiator capable of being made in sections and used as an individual section or in multiple sections, the characteristics of which radiator will be superior to the radiators now known in the art by reduction in weight, by the occupancy 10 of less space and by performing the same heat transfer work equal to or in greater degree than the radiators of the prior art while, at the same time, provide a stronger construction in order to stand higher internal pressures than at present 15 possible in the art with existing radiators.

It is a further object to provide a radiator which offers materially less friction to the passage of air over the radiator by reducing the resistance to the passage of air while, at the 20 same time, increasing the heat transfer.

It is a further object to provide a radiator, whether compared on the basis of equal friction or equal velocity, which will produce the foregoing superior features.

I have been successful in solving the problem of reducing the weight, the amount of space occupied and the friction, and of increasing the rate of heat transfer by the radiator of my invention, which is particularly useful in connection with heat transfer systems where air is blown over the radiators. My invention makes possible high efficiencies, as hereinafter pointed out, while, at the same time, not changing the material, cast iron being employed.

Specifically, the foregoing advantageous results over the prior art have been secured by causing the fluid stream, such as air, to undulate to a point approaching, but never attaining, detached flow, so that, at the upstream point of flow deflection, the pressure and velocity are materially increased while the eddies are consequently reduced in diameter and acceleration, thus permitting more intimate contact at an increased velocity with the more nearly virgin air 45 near the center of the stream and a continual

removal of the fluid particles from the center of the stream to the boundary. There is a consequent reduction of velocity on the downstream cavity but, as this decreased velocity is immediately followed by an increased velocity 5 on the same boundary surface by the next undulation, the diameters of the eddies are prevented from increasing to that size heretofore encountered in non-undulating flow as the time element between the alternating high velocity-high pressure and low velocity-low pressure point is insufficient to admit of reformation of an eddy diameter encountered in non-undulating flow.

In my invention, due to the alternate increased and decreased velocities and pressures, 15 the heated boundary particles of the fluid are continually being replaced by cooler inner stream particles, thus producing a greatly increased heating effect on the entire body of the fluid and producing maximum heat transfer 20 from the prime to the secondary fluid, requiring minimum space, and requiring minimum material in the containing boundaries.

The energy expenditure necessary to produce such undulations is proportional to the angular 25 change in direction added to the increased frictional resistance due to the velocity increase. The loss due to angularity is sufficiently small as to be negligible. A greatly increased rate of 30 heat transfer is, therefore, produced by undetached undulatory flow at an expenditure of a negligible increase in energy.

To secure the foregoing result in my method of heat transfer, I provide a steam-containing 35 body whose sides carry gently undulatory fins which preferably completely encircle the steam containing body. The body itself is longer in a plane at right angles to the direction of the fins than in the direction of the fins and the steam or other heating or cooling fluid or gas is arranged at right angles to the direction of the fluid or gas passing over the outside of the body guided by the undulatory fins. The undulations of the fins or ribs must be of such a character 40 as to preserve the principle of this invention of undetached undulatory flow.

This provides a sufficient body of moving air with the minimum resistance thereto to permit 45 adequate velocity while securing maximum heat transfer.

will materially affect the growth, size and velocity of the eddies interposed between the main fluid stream and the boundary surface.

Turning to the other customary construction in the art of fins having a series of portions at sharp (Fig. 9) angles to one another or having fins that are sharply undulatory giving marked changes in direction, then the angle of undulation will be increased materially and the air flow 5 will be changed in direction a number of times during the passage between the fins. The fluid flow will be deflected sharply with an expenditure of energy relative to the acuteness of angularity of the air path. The main stream will 10 become detached from the boundary forming a low pressure area on the down stream, acute angle region between the stream and the boundary and a swirl or large eddy will be formed having a diameter approaching the maximum distance between the parallel of the fluid stream 15 and the maximum depth of the boundary therefrom. The surface will be thus deprived of intimate contact with the fluid losing its value in the transfer of convected heat, thus materially 20 reducing its effectiveness.

The formation and subsequent detachment of these larger eddies impose greatly increased turbulence without intimate contact with a consequent increase of energy expended in producing flow between these two extremes, i. e., parallel straight flow and alternate detached surface flow, which has characterized the prior art; I have found that there is a principle of construction which, when practiced, will produce the 25 greatest transfer of heat for the least energy expenditure with the minimum area of boundary wall permitting a marked decrease in the weight of cast iron employed, a decrease in size, a reduction in resistance to air flow and without a 30 decrease in velocity.

The principle I have embodied in my invention, in my construction and method of operation is to so arrange in undulations of the fins as to secure a continuous undetached contact 35 with all surfaces of the boundary which I call undetached undulatory flow (Figs. 1 to 8 and Fig. 10).

To the foregoing as a feature of my invention, I have added means for entry and exit of the 40 air so as to minimize the losses due to changes in velocity and to maintain fluid contact with both entry and parallel walls. At the point of entry, the vena contract, which occurs with a sharp-cornered wall, is entirely avoided.

By the practice of the invention embodying 45 my principles and methods, it is possible to use undulations vertically with respect to the stream line but also horizontal with respect to the main line of the stream.

Referring to Figure 8, it will be seen that it 50 shows a diagram illustrating the use of parallel wall fins, the walls being designated 13. The cone of entering air is designated 14 and two relatively thick streams of turbulent eddies 55 serve to insulate the body 14 of air from the hot walls 13 thereby cutting down heat transfer. This parallel flow type is inefficient for the reasons heretofore pointed out.

Turning to the other form characteristic of 60 the prior art, (Fig. 9) which either consists of sharp undulations as shown, or angular undulations, it will be noted that the cone of air has an even narrower or thinner cone of air designated 65 16. This cone of air only touches at intervals 70 at 17 the sharply bent walls 18 while the spaces

therebetween in the deep valleys 19 are filled with very large areas of turbulent air 20. This illustrates the detached undulatory flow characteristic of the other class of the prior art 75 which is unsuccessful for heat transfer.

Turning to Figure 10, which illustrates the present invention, it will be noted that the body of air 21 passing between the fins 7 engages over a relatively long area indicated at 22 the adjacent areas on the surfaces of the fins 7 and 10 whatever small eddies are set up as at 23 are of very minor character but are sufficient to cause movement of the hot air which is quickly heated due to the diameter of the eddies 23 being small 15 and due to the fact that these eddies move easily into portions of the body of the cooler air 21 and exchange places with other small eddies of cold air, thereby effecting a rapid heat transfer. It will be further apparent upon studying these 20 diagrams, which illustrate graphically the practical tests and laboratory research results, that I have secured, that the body of air passing through in Figure 10 is much larger than in Figures 8 and 9. Furthermore, the area of contact 25 of the body 21 of air in Figure 10 is much greater than in Figures 8 and 9. It will be observed that the deep areas of turbulence in Figures 8 and 9 which act as insulation areas between the heated fins and the body of cold air 14 or 16 are absent in Figure 10 of the present invention. 30 These factors are vital in a blast radiator where resistance to air flow must be avoided, and where quantity of air delivered suitably heated with the least expenditure of horsepower to move the air is the primary criterion of success.

By employing a construction which practices the principle of undetached undulatory flow explained herein, the present construction avoids the disadvantages and pitfalls of the prior art 35 and makes possible the use of an economical, 40 forced draft radiator.

It will be understood that I desire to comprehend within my invention such modifications as may be necessary to adapt it to varying conditions and uses.

Having thus fully described my invention, what I claim as new and desire to secure by Letters Patent, is:

1. In combination, a heating body arranged for heating fluid to flow therein over unimpeded 50 surfaces, a plurality of parallel undulating fins arranged on the exterior of the body for guiding air thereover, said undulations being sufficient to cause the air to undulate to a point approaching but never attaining detached flow over the 55 heated surfaces of the body and fins, and means comprising continuations of the fins at the entry and exit from the space therebetween for guiding the air into and from between the fins without turbulence.

2. In a radiator, a body forming a heating chamber having oppositely-disposed inlet and outlet openings, said body being rectangular in cross section, and a plurality of undulatory fins mounted on the side walls thereof, the undulations of said fins having a maximum deflection of approximately one-twenty-seventh of the distance between centers of the undulations below and above a center line of the fins measured with respect to the distance between the centers 70 of adjacent undulations.

3. In a radiator, a body forming a heating chamber having oppositely-disposed inlet and outlet openings, said body being rectangular in cross section, and a plurality of undulatory fins 75

- mounted on the side walls thereof, the undulations of said fins having a vertical deflection of approximately 11/64ths to 13/64ths of an inch above and below a center line of the fins measured with respect to the distance between the centers of adjacent undulations, and the space between adjacent fins being an approximate average width of one-half inch.
4. In a radiator, a body forming a heating chamber having oppositely-disposed inlet and outlet openings, said body being rectangular in cross section, and a plurality of undulatory fins mounted on the side walls thereof, the undulations of said fins having a vertical deflection of approximately 11/64ths to 13/64ths of an inch above and below a center line of the fins measured with respect to the distance between the centers of adjacent undulations, and the space between adjacent fins being an approximate average width of one-half inch, and the depth between said fins being slightly greater than one-half inch.
5. In a radiator, a body forming a heating chamber having oppositely-disposed inlet and outlet openings, said body being rectangular in cross section, and a plurality of undulatory fins mounted on the side walls thereof, the undulations of said fins having a vertical deflection of approximately 11/64ths to 13/64ths of an inch above and below a center line of the fins measured with respect to the distance between the centers of adjacent undulations, and the space between adjacent fins being an approximate average width of one-half inch, and the depth between said fins being slightly greater than one-half inch.
6. In a radiator, a body forming a chamber having oppositely-disposed inlet and outlet openings, said body being rectangular in cross section, and a plurality of encircling undulatory fins, said fins being heavier across the ends of the body than on the sides.
7. In a radiator, a body forming a chamber having oppositely-disposed inlet and outlet openings, said body being rectangular in cross section, a plurality of encircling undulatory fins, said fins being heavier across the ends of the body than on the sides, and wedge-shaped throughout their length.
8. In a radiator, a body forming a chamber having oppositely-disposed inlet and outlet openings, said body being rectangular in cross section, a plurality of encircling undulatory fins, said fins being heavier across the ends of the body than on the sides, and wedge-shaped throughout their length, the ends of said body and the ends of said fins tapering to an edge forming a ridge on the ends of the body.
9. In a radiator, a body forming a chamber having oppositely-disposed inlet and outlet openings, said body having flat side walls and a plurality of encircling undulatory fins, each of said fins extending entirely around said body.
10. In a radiator, a body forming a chamber having oppositely-disposed inlet and outlet openings, said body being rectangular in cross section with flat side walls and a plurality of encircling undulatory fins, each of said fins extending entirely around said body and said fins having their outer margins parallel to the surface of the side walls of the radiator body.
11. In a radiator, a body forming a chamber having oppositely-disposed inlet and outlet openings, said body being rectangular in cross section with flat side walls and a plurality of encircling undulatory fins, each of said fins extending entirely around said body and said fins having their outer margins parallel to the surface of the side walls of the radiator body and spaced from one another a distance equal to approximately the height of one of them whereby a channel is formed for the passage of air of substantially uniform cross section between the metal walls defining the channel.
12. In a radiator, a body forming a chamber having oppositely-disposed inlet and outlet openings, said body being rectangular in cross section with flat side walls and a plurality of encircling undulatory fins, said fins having their outer margins parallel to the surface of the side walls of the radiator body and spaced from one another a distance equal to approximately the height of one of them whereby a channel is formed for the passage of air of substantially uniform cross section between the metal walls defining the channel, and said radiator body wall and fins being of substantially equal thickness.
13. In a radiator, a body forming a chamber having oppositely-disposed inlet and outlet openings, said body being rectangular in cross section with flat side walls and a plurality of encircling undulatory fins, said fins having their outer margins parallel to the surface of the side walls of the radiator body and spaced from one another a distance equal to approximately the height of one of them whereby a channel is formed for the passage of air of substantially uniform cross section between the metal walls defining the channel, said radiator body wall and fins being of substantially equal thickness, the outer portions of the fins tapering so that the lesser the heat the lesser the metal to insure uniform heat distribution to the air in the passageway formed by the radiator body wall and undulatory fins.
14. In combination, means for forming a passageway, a plurality of parallel interconnected radiator sections arranged transversely of the passageway, and a plurality of similar sections arranged behind in staggered relationship with respect to the preceding sections, and a plurality of undulatory fins mounted on each of said sections, the fins of each section being disposed opposite to the fins of the adjacent section in spaced relationship thereto, and means of forcing a blast of air over said sections and between them.
15. In combination, means for forming a passageway, a plurality of parallel interconnected radiator sections arranged transversely of the passageway, a plurality of similar sections arranged behind in staggered relationship with respect to the preceding sections, and a plurality of undulatory fins mounted on each of said sections, the fins of each section being disposed opposite to the fins of the adjacent section in spaced relationship thereto, and means of forcing a blast of air over said sections and between them, said fins being so arranged as to provide an undulatory movement for the air approaching but never attaining detached flow over the heated surfaces of the radiator sections.
16. In a radiator, a body forming a heating chamber and a plurality of spaced ribs on the sides thereof inclined from one end of the rib to the other, said ribs being undulatory, said undulations varying from the center axis of the undulatory rib from 11/64ths to 13/64ths of an inch.

17. In a radiator, a body forming a heating chamber and a plurality of spaced ribs on the sides thereof inclined from one end of the rib to the other, said ribs being undulatory and 5 completely encircling the heating body.

18. In combination, a heating body arranged for heating fluid to flow therein, a plurality of parallel undulating fins arranged on the exterior of the body for guiding the air thereover, said 10 fins extending beyond the ends of the heating body, each fin continuously encircling said body.

19. In combination, a heating body arranged for heating fluid to flow therein, a plurality of parallel undulating fins arranged on the exterior 15 of the body for guiding air thereover, said fins extending beyond the ends of the heating body, each of said fins entirely encircling said body and the undulation of said fins being sufficient to cause the air to undulate to a point approaching but never attaining detached flow over the 20 heating surfaces of the body and fins.

20. In combination, a heating body arranged

for heating fluid to flow therein, a plurality of parallel undulating fins having crests and troughs arranged on the exterior of the body for guiding the air thereover, the troughs of said undulations extending below the crest to an extent between 11/64ths and 13/64ths of an inch from a horizontal line to which the crests of the undulations are tangent.

21. In combination, a heating body arranged for heating a fluid to flow therein, a plurality 10 of parallel undulating fins arranged on the exterior of the body having crests and troughs for guiding the air thereover, the troughs of said undulations extending below the crest to an extent between 11/64ths and 13/64ths of an inch 15 from a horizontal line to which the crests of the undulations are tangent, said undulations being sufficient to cause the air to undulate to a point approaching but never attaining detached flow over the heated surfaces of the body 20 and fins.

OTTO G. WENDEL.
